UNITED STATES PATENT OFFICE.

CHARLES P. MORTON, OF CINCINNATI, OHIO.

CUTTER-HEAD FOR LAST-LATHES.

1,326,135.

Specification of Letters Patent. Patented Dec. 23, 1919.

Application filed April 11, 1917. Serial No. 161,140.

To all whom it may concern:

Be it known that I, CHARLES P. MORTON, a citizen of the United States of America, and resident of Cincinnati, in the county of 5 Hamilton and State of Ohio, have invented a new and useful Improvement in Cutter-Heads for Last-Lathes, of which the following is a specification.

An object of my invention is a cutter head 10 of compact form, comprising roughing and smoothing cutters, by which a drawing cut may be made.

Another object of my invention is a combined roughing and finishing cutter head, in 15 which knives of high grade steel may be used without increasing the cost of the cutter head.

A further object of my invention is a cutter head, in which the labor necessary to 20 keep the knives sharp, is small.

A further object of my invention is a cutter head of compact form.

These objects are attained by the means described in the specification and illustrated 25 in the accompanying drawings, in which,

Figure 1 is a plan view of my improved cutter head.

Fig. 2 is a side elevation of my improved cutter head.

Fig. 3 is a perspective view of my improved cutter head.

Fig. 4 is a perspective view of one of the finishing cutters and fastening means employed therefor.

Fig. 5 is a front elevation of a cutter head embodying my invention, and a shoe last mounted in position for being operated upon by my cutter.

My improved cutter head consists of a 40 body 5, which is in the form of a frustum of a cone, and has at its larger end longitudinally extending lugs 6 and 7, whose periphery conforms to the lines of the frustum of the cone. Adjacent to the lugs 6 and 45 7 are longitudinal slots 12, which are at an angle to the radii of the body portion. The body portion 5 and lugs 6 and 7 are made integral and are formed from machine steel. Roughing cutters 13 consist of thick 50 blades of tool steel and have beveled cutting edges. When the knives are mounted in their slots, the inner edges of the bevel are flush with the adjacent surface of the body 5, and the cutting edges project beyond 55 the periphery thereof. The knives are held in place by means of set screws 15, which

are seated in bores, which are formed in the body 5, adjacent to the slots 12 and at a slight angle to a tangent to the periphery of the body 5. The set screws 15 engage recesses 16, which are formed in the knives 13. The knives 13 are made of a length, such that their outer edges project slightly into the annular paths of the finishing cutters.

The finishing cutters 8 and 9 are made in 60 the form of frustums of cones and have circular beveled cutting edges 11. These finishing cutters have central perforations to receive screws 10, which engage holes centrally located in the lugs 6 and 7. To hold 70 the finishing cutters 8 and 9 from rotation, I provide keys 8^a and 9^a, which engage radial slots upon the back of the cutters and longitudinal slots upon the inner faces of 75 the lugs 6 and 7.

The cutter is mounted upon its spindle 15, with the smaller end of the body portion nearest to the bearing 16 of the spindle. In operation, the cutter is moved past its work, so that the axis of the spindle is at an angle 80 to the longitudinal axis of the work, and the bearing 16 of the spindle moves past the work in advance of the cutter, so that the roughing knives 13 and 14, as well as the finishing knives 8 and 9 operate upon the 85 work with a drawing cut as distinguished from a chopping cut.

The roughing knives 13 and the finishing knives 8 and 9 may be made of the expensive steel, known as "tool steel", because the 90 amount of material in them is small compared with that in the body portion 5. This tool steel holds its cutting edge for a much longer time than ordinary steel. Moreover, the form of the roughing cutters 13 is such 95 and the manner of mounting them in the body 5 is such, that they are readily removed and sharpened. The finishing cutters may be moved to four different positions by removing the keys, before they require removal from the head for resharpening.

Since the lugs 6 and 7 are formed longitudinally upon the body portion 5, and conform with the general contour of the body 105 portion 5, and since the cutting edges of the finishing cutters and of the roughing cutters conform to the general outline of a frustum of a cone, I am able to provide a knife which has a compact form.

What I claim is:

1. A cutter head for last lathes comprising

ing a spindle, a body portion in the shape of a frustum of a cone and mounted upon the spindle with its smaller end inward, straight edged cutters mounted longitudinally upon the smaller end of the body portion and curved edged cutters mounted upon the larger end of the body portion and with their axis transverse to the spindle.

2. A cutter head for last lathes, comprising a body portion having longitudinal slots in its sides and longitudinally extending lugs at its end, longitudinal roughing knives mounted in the longitudinal slots, and circular finishing knives mounted upon the lugs.

3. A cutter head having a body portion of the shape of the frustum of a cone, longitudinal slots in the sides of the body portion, and longitudinal lugs upon the larger end of the body portion, longitudinal roughing knives in the slots, and circular finishing cutters mounted upon the lugs. 20

In testimony whereof, I have hereunto subscribed my name this 9th day of April, 1917.

CHAS. P. MORTON.
